UNITED STATES PATENT OFFICE.

EDNA Z. TEAM, OF CAMDEN, SOUTH CAROLINA.

DESIGN FOR A PEN-WIPER.

46,188.

Specification for Design.

Patented July 28, 1914.

Application filed May 14, 1914. Serial No. 838,584. Term of patent 7 years.

To all whom it may concern:

Be it known that I, EDNA Z. TEAM, a citizen of the United States, residing at Camden, in the county of Kershaw and State of South Carolina, have invented a new, original, and ornamental Design for Pen-Wipers, of which the following is a specification, reference being had to the accompanying drawing, forming part thereof.

Figure 1 is a perspective view taken from the front of a pen-wiper showing my new design: and, Fig. 2 is a similar view taken from the rear thereof.

I claim:

The ornamental design for a pen-wiper, as shown.
